(57) **CLAIM**

The ornamental design for a vanity mirror, as shown and described.

DESCRIPTION

FIG. 1 is a front, left, top perspective view of a vanity mirror, showing my new design;

FIG. 2 is a rear, right, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged, rear, right, bottom perspective view of area 9 in FIG. 2.

The dash-dash broken lines in the drawings illustrate the portions of the vanity mirror, which form no part of the claimed design.

The dash-dot-dash broken lines encircling enlarged areas of the vanity mirror in FIG. 2 and FIG. 9 depict the boundary of the enlargements, and form no part of the claim thereof.
